US00D960614S

(12) **United States Design Patent** (10) Patent No.: **US D960,614 S**
(45) Date of Patent: **** Aug. 16, 2022**

(54) **RETAIL FIXTURE**

- (71) Applicant: **Apple Inc.**, Cupertino, CA (US)
- (72) Inventors: **Alice Marlin Brugger**, San Francisco, CA (US); **Manuel Dejesus**, San Francisco, CA (US); **Joshua Robert Edwards**, Santa Cruz, CA (US); **Jean-Marc Gady**, Los Altos, CA (US); **Wesley Bryan Hamm**, San Francisco, CA (US); **Russell John Kaaihue Heirakuji**, Cupertino, CA (US); **Allison Inouye**, San Francisco, CA (US); **Moritz Wilsberg**, Rheinbreitbach (DE)
- (73) Assignee: **Apple Inc.**, Cupertino, CA (US)
- (**) Term: **15 Years**
- (21) Appl. No.: **29/817,837**
- (22) Filed: **Dec. 3, 2021**

Related U.S. Application Data

- (63) Continuation of application No. 29/747,622, filed on Aug. 24, 2020, now Pat. No. Des. 937,612, which is a continuation of application No. 29/727,169, filed on Mar. 9, 2020, now Pat. No. Des. 893,923, which is a continuation of application No. 29/681,841, filed on Feb. 28, 2019, now Pat. No. Des. 877,548, which is a continuation of application No. 29/656,127, filed on Jul. 10, 2018, now Pat. No. Des. 867,035.

CLAIM

The ornamental design for a retail fixture, as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the retail fixture that form no part of the claimed design.

1 Claim, 5 Drawing Sheets
